UNITED STATES PATENT OFFICE.

MORTON C. TALCOTT, OF HARTFORD, CONNECTICUT.

TRANSMISSION-GEARING.

No. 809,540.

Specification of Letters Patent.

Patented Jan. 9, 1906.

Application filed October 14, 1905. Serial No. 282,790.

To all whom it may concern:

Be it known that I, MORTON C. TALCOTT, a citizen of the United States, residing at Hartford, in the county of Hartford and State of Connecticut, have invented a new and useful Transmission-Gearing, of which the following is a specification.

This invention relates to a mechanism for connecting gearing with a shaft for the purpose of varying the speed of the shaft.

The object of the invention is to provide a very simple mechanism for throwing first one clutch and then another by a simple movement for the purpose of connecting the different speed-gears with the shaft they are on.

The loose gears of the gearing which is illustrated are designed to be connected with their shaft by band-clutches which are operated by levers that are oscillated by means of racks and pinions so arranged that first one will be oscillated, then another, and another by the continued movement of the operating-lever in one direction.

Figure 1 of the accompanying drawings shows a vertical section of so much of the gearing as is necessary to comprehend the invention. Fig. 2 shows a section, on a larger scale, taken through the rack-bar and one of the clutch-lever-oscillating pinions. Fig. 3 shows a side elevation of the same parts of the gearing as are shown in Fig. 2. Fig. 4 shows a face view of a clutch. Fig. 5 shows a section taken through the clutch.

Loosely mounted on the shaft 1 are gears 2, 3, and 4 of different diameters. The hubs of these gears are enlarged, so as to form boxes 5. Keyed to the shaft in each box is a drum 6, and encircling each drum is a band 7. One end of each band is hinged directly to the walls of the box that it occupies and the other end is jointed to a lever 8, that is hinged to the walls of the box.

Movable on the shaft adjacent to each drum is a grooved wedge-collar 9. The inner end of each lever 8 may have a block 10, provided with a roll 11. This block is adjustable in and out on the end of the lever by means of a thumb-screw 12. This roll at the end of the lever is arranged to ride on the face of the wedge 9. When the wedge is driven into the box, this lever is forced outwardly, and when thus moved the band is contracted and tightened around the drum, so as to fasten together the drum on the shaft and the box that is a part of the gear. When the wedge is drawn out of the box, the lever

loosens the band and releases the drum, so that the box and gear will be loose on the shaft.

Extending parallel with the shaft and having a longitudinal movement is a bar 13. This bar is connected with a lever 14, which is oscillated by any desired means. On the bar at considerable intervals are several short racks 15, 16, and 17. Adapted to engage with these racks are pinions 18, 19, and 20, mounted on arbors 21, held by brackets 22, attached to the casing 23. Connected eccentrically with each of these pinions is a link 24, that is connected with a lever 25. The upper ends of these levers are preferably forked and are adapted to engage rings 26, lying in the grooves of the wedge-collars 9. As a result of the eccentricity of the pin which connects each link with its pinion the rotations of the pinions 75 oscillate the levers. Connected with each pinion is a disk 27, in one face of which are sockets 28. Projecting from the brackets which support the pinion arbors are spring-plungers 29, the outer ends of which are adapted 80 to enter the sockets in the disks, so as to hold the pinions against accidental movements.

When the rack-bar is first moved forwardly, the rack 15 rotates the pinion 18 and causes the oscillation of the lever, which 85 causes a clutch to connect the gear 2 with the shaft. A further movement of the rack-bar in the same direction rotates the pinion 18 in such manner that the clutch will release the gear 2. By this time the rack 16 engages the pinion 19, and then this pinion is rotated in such manner that a clutch will connect the gear 3 with the shaft. When the rack-bar is moved forward farther, the rack 16 rotates the pinion 19, so that the clutch releases the 95 gear 3, and then the rack 17 rotates the pinion 20, so that a clutch will connect the gear 4 with the shaft.

With this mechanism the movement of the rack in one direction rotates first one pinion, 100 then another, and then the other. These parts are so designed that each pinion is given a complete revolution by each rack, the first half of the revolution oscillating the lever so as to set the clutch and the last half to 105 release the clutch. The friction-pins and the disks hold the pinions in position, so that the racks will properly engage them.

The invention is shown in the drawings and described throughout the specification as designed for connecting toothed gears to a shaft; but the invention is equally applicable

without any change for connecting friction gears or pulleys to a shaft.

The invention claimed is—

1. In a transmission-gearing, a shaft, gears of different diameters loose on the shaft, clutches adapted to connect the gears with the shaft, a bar bearing racks, pinions adapted to be successively rotated by the racks, and connections between the pinions and the clutches for operating the clutches, substantially as specified.
2. In a transmission-gearing, a shaft, gears of different diameters loose on the shaft, a drum keyed to the shaft adjacent to each gear, a clutch-band encircling each drum and connected with the adjacent gear, a wedge movable upon the shaft for tightening each band upon the adjacent drum, a bar bearing racks, pinions adapted to be successively rotated by the racks, and a connection between the pinions and the wedges for moving the wedges when the pinions are rotated, substantially as specified.
3. In a transmission-gearing, a shaft, gears of different diameters loose on the shaft, a clutch for connecting each gear with the shaft, a bar bearing racks, pinions adapted to be successively rotated by the racks, me-

tions) means for retaining the pinions against rotation when disengaged from the racks, and levers connected with the clutches and adapted to be oscillated by the rotations of the pinions, substantially as specified.

4. A power-transmission element consisting of a shaft, a gear loose on the shaft, a lever connected with the gear, a drum fixed to the shaft adjacent to the gear, a band encircling the drum and having one end connected with the gear and the other end attached to the lever that is connected with the gear, and a wedge movable longitudinally on the shaft and adapted to engage the lever for contracting the band upon the drum, substantially as specified.

5. In a transmission-gearing the combination of clutches, a bar bearing racks, pinions adapted to be successively rotated by the racks, and connections between the pinions and the clutches for operating the clutches by the rotations of the pinions, substantially as specified.
